FIREPLACE DISPLAY

Otto Schlett, Bronx, N. Y.

Application March 4, 1941, Serial No. 381,628

11 Claims. (Cl. 272—15)

This invention relates to display devices in general, and particularly to fireplace displays, intended to create the impression of live fire emanating from imitation fuel, such as artificial wood logs, coal, etc.

One of the objects of the present invention is to provide an extremely simple and inexpensive device of this kind, wherein easily constructed light-controlling means are employed, which are designed to direct light rays against a steeply inclined, translucent screen upon which the images of long, ever-changing, colored flame, sparks, smoke or clouds are impressed, and wherein such images of varicolored flames are caused to produce the effect of moving from without towards the center and also in upward direction, to create a realistic imitation of actual fire, with smoke and occasionally sparks, drawing up the chimney.

Another object of this invention is to provide in my device light intensity control means, whereby direct light, as well as major portions of reflected light, and images created thereby, are caused to become alternately and gradually visible and obscured, while the images projected upon a screen continuously change in colors.

Another object of the present invention is to provide in connection with a light source employed in my device, regulating means for controlling the speed of the mechanism actuating the light controlling devices.

The foregoing and still further objects and important advantages of the present invention will become more fully apparent from the ensuing description and the accompanying drawing, which latter, although showing a specific construction of my invention, is by no means intended to restrict the same to the actual disclosure, and wherein:

Fig. 1 is a front elevation of my device;

Fig. 2 is a vertical cross sectional view through the device shown in Fig. 1, including imitation wood logs placed in front thereof;

Fig. 3 is a horizontal cross section through my device taken on line 3—3 of Fig. 2;

Fig. 4 is a top view of the light source and motive arrangement of my device;

Fig. 5 is a side elevation thereof partially in section; and

Fig. 6 is a top view of my device in its collapsed position, ready for shipment.

Referring now specifically to the figures, numeral 10 denotes the back wall of my device, from which extend upwardly-broadening side walls 11. The latter are joined with the back wall by a top

member 12, which is provided with a plurality of vent holes 13, and a base or bottom member 14. Between the side members 11 is arranged a translucent screen 15, made of either ground glass or a film material, such as a sheet of Celluloid, which screen is sharply inclined for reasons hereinafter explained. Below the screen is provided an opening, and in this opening is secured to back member 10 a hinged platform 16, which may be pivoted about point 17 so that the front portion of the platform can be swung down, as indicated in broken lines in Fig. 2. Supporting the movable platform portion is an upright 18, which is hinged at 19 and may be collapsed to a flat, downward position, indicated in broken lines in Fig. 1. Movable secured to the inclined edges of side walls 11 are two adjustable wings 20, which latter, when the device is to be shipped, may be swung towards screen 15, as indicated in Fig. 6, so that the latter will not be damaged.

In front of the opening, and extending somewhat above the lower edge of panel 15, an arrangement of actual fuel or of a fuel imitation is placed, such as imitation wood logs 21 indicated in Fig. 2. Supported by hinged platform 16 are sockets 22 for the reception of electric bulbs 23, which are surrounded by fixed, non-transparent cylinders 24. The latter are preferably secured to platform 16, as shown at 25, and are provided with bottom vent openings 26. The passage of air through these vent openings may be regulated by a sliding sleeve 27, provided with a handle 28 for facilitating its operation. When the sleeve is lowered over openings 26 the draft created by the heat of bulb 23 may be cut down. When the sleeve clears openings 26, the full amount of air is allowed to pass up cylinder 24. It will be observed that bulbs 23 and their cylinders extend partially outwards from the compartment below screen 15.

Above each cylinder is mounted a fan 29, which is preferably supported by a fixed bracket 30, secured at 31 to rear wall 10 of the device. The free end of the bracket is bent upwards and terminates into a sharply pointed prong 32, upon which rests the conically shaped center 33 of fan 29. Extending from and secured to this raised fan center is a thin wire rod 34, which is guided at its upper portion in an eye of bracket 35 (see Fig. 2), so that both the fan and rod 34 may freely rotate, when heated air emanating from cylinder 24 causes the fan to operate.

Attached to and slightly extending from wire rod 34, which latter is preferably very light and resilient, is a number of spaced, brightly polished

spangles 36, which are inclined somewhat towards bulbs 23, so that they alternately reflect light from the latter onto screen 15 as their position changes. These spangles are preferably supported by small coils of spring wire members 37, which frictionally engage rod 34, and are adjustable in respect thereto, so that the spangles may be moved to various heights upon rod 34.

Secured above bulbs 23 to rear wall 10 of the device is a mirror 38 (see Fig. 2). Above the mirror are placed two superimposed, inclined sheets or panels, indicated at 39 and 40, see Figs. 2 and 3. Upon the lower panel 39, which may be made of glass or any other suitable transparent material, such as a cellulose film, there are provided zigzag or criss-cross formations of translucent, narrow strips 41 of differently colored material, preferably including green, yellow, red, blue and orange colors. With panel 40 there are arranged opaque tongue-shaped configurations 42, between which are provided similar, light-passing tongues 43. Panel 40 may be made either from transparent material, with opaque tongues 42 painted or otherwise applied thereto, or may be fabricated in the form of a stamping from solid material, such as sheet metal, with tongues 42 stamped out from the metal.

It will be observed that tongues 42 as well as strips 41 are so positioned that their configurations are directed from the ends of panels 39 and 40 towards their centers, providing a substantially herring-bone resembling design. This arrangement is made for the purpose of providing an illusion of flames moving from without towards the center of the display. Attention is called to the substantially midway position of rods 34, extending from the fans, in respect to screen 15 and panels 39 and 40.

Referring to Figs. 4 and 5, it will be observed that on top of fan 29 there is placed a thin and lightweight curved body 44, which is intended to alternately prevent and permit the passage of light through the fan, as the latter and body 44 rotate above bulb 23. This curved body may be either a separate stamping, secured to the fan, or it may form a part of the fan body itself. Such construction being obvious, a special illustration thereof is omitted.

Operation

It will be observed from Figs. 1 and 3 that curved shapes 44 mounted on top of fans 29 are disposed in opposite positions to one another, and that also the fans are arranged to rotate in opposite directions.

As the air within dark cylinders 24 becomes heated, a draft is created through passages 25 of the cylinders in upward direction. Heated air escaping from the top of the cylinders causes fans 29, segments 44 and rods 34 to rotate towards one another. A substantial portion of the light escaping through the openings between the fan blades will strike imitation fuel arrangement 21, placed in front of the device. Another major portion of the light passing through the fans will be reflected by mirror 38, through panels 39 and 40, against screen 15. The reflected light is forced to first pass through translucent colored strips 41 and then through open fields 43 of upper panel 40. The resulting light images appearing upon screen 15 will resemble animated flame-tongue formations. Since screen 15 is sharply inclined in respect to mirror 38, these flame-tongue images appear relatively long and will diminish in light intensity towards their top ends.

This, together with the fluctuating light intensities caused by rotating segments 44, provides an impression of the flame-tongues dissolving into smoke or clouds. The colored strips 41 of lower panel 39 vary the coloring of the tongues, and in addition there will appear on the screen at various heights and at various frequencies tiny spark-resembling flashes, produced by minor light portions released through the fan openings being reflected by moving spangles 36. Thus a very realistic illusion of live flames, moving inwards and upwards, and of smoke and sparks, will appear upon screen 15.

Obviously I prefer to employ two spaced light sources to produce the desired light effects upon the screen. However, very satisfactory flame imitations may be effected with but one light source, if the latter is placed below the screen center, in which event a somewhat differently shaped segment for controlling the light intensities of the images is employed.

It will be observed that the mechanism of the device is extremely simple, and although being so simple, will create a very effective illusion of flames, smoke and sparks emanating from the imitation fuel placed in front of the device. While I have shown and described specific forms and structures employed in my device, it is quite obvious that changes and improvements may be incorporated therein, without departing from the broad scope of my invention, as expressed in the annexed claims.

I claim:

1. In a fireplace display device, the combination with a translucent screen, of a light source, a light reflector adapted to project major light portions from the light source upon the screen, a plurality of superimposed panels interposed between the reflector and the screen, one of the panels having opaque and light-passing fields, another panel having an arrangement of colored fields, a movable member interposed between the light source and the reflector and provided with means for alternately obscuring major light portions from and passing them against the reflector, and other means carried by said movable member for alternately reflecting minor light portions against the screen at different heights.

2. In a fireplace display device, as set forth in claim 1, said light source being surrounded by an opaque, fixed hollow member having air inlet passages at its bottom, and means adjustable relative to said hollow member for controlling the amount of air passing through the passages.

3. In a fireplace display device, a substantially closed, vented hollow structure having an open space at its lower end, a collapsible light source support secured to said structure in its open space, at least two light sources mounted upon said support, a hollow, opaque member surrounding each light source and being open at the top and having air passages at the bottom, means for controlling the amount of air passing through said passages, a translucent screen mounted in said structure above the light sources and being sharply inclined in respect to the latter, a reflector disposed above the light sources and facing the screen, a plurality of superimposed, spaced panels interposed between the reflector and the screen, one of the panels having opaque and light-passing fields, another panel supporting an arrangement of narrow, colored translucent fields, the fields of both panels being inclined from the panel ends towards their centers, a fan operatively mounted above the light source

and adapted to be actuated by heated air issuing from the top of said hollow member, a journaled rod associated with and extending above the fan and supporting a plurality of small light reflectors, and a light-passage controlling means provided with said fan.

4. In a fireplace display device, as set forth in claim 3, and movably mounted extension wings associated with said structure and adapted to be swung into adjacent position in respect to said screen.

5. In a fireplace display device, as set forth in claim 3, said light sources being disposed below and substantially midway in respect to the screen and said panels.

6. In a device of the class indicated, the combination with a light source, of a translucent screen sharply inclined in one direction in respect to the latter, a major light reflector, an images-producing panel interposed between the reflector and the screen, said panel being inclined in an opposite direction to that of the screen in respect to the light source, a rotary member above the light source, light intensity controlling means and miniature light reflecting elements operative with said rotary member.

7. In a device of the class indicated, the combination with at least two spaced light sources, of a translucent screen disposed above and being sharply inclined in one direction in respect to the light sources, a major light reflector opposite said screen, a plurality of spaced, superimposed panels interposed between said reflector and the screen and being inclined opposite thereto in respect to the light sources, a light-passing rotary member above each light source, provided with light intensity controlling means and a plurality of inclined, spaced miniature light reflectors, said panels having images-forming elements, adapted to produce upon the screen, due to the inclined position of the latter, elongated flame images, said rotary members and said light

intensity controlling means being adapted to cause such images to move not only in upward direction, but also in the directions from the sides of the screen towards its center, and said miniature reflectors being adapted to produce upon the screen spark-resembling images.

8. In a device of the class described, as set forth in claim 7, the rotary members above the two light sources being constructed and arranged to rotate towards each other, and said light intensity controlling means being arranged at positions opposite to each other, said rotary members and said intensity controlling means, through their rotary movements towards one another, causing the stated movements of the flame images upon the screen.

9. In a display device, at least one light source, at least one translucent screen for the reception of light rays from the light source, means for directing a major portion of light rays against the screen, means interposed between the light ray directing means and the screen for producing images upon the latter, movable means interposed between the light source and the light ray directing means for controlling the intensity of light rays released against the screen, means operative with said movable means for directing minor light reflections upon the screen, and means for controlling the speed at which said movable means operate.

10. In a display device, as per claim 9, said screen being sharply inclined towards the light source in one direction, said images producing means being inclined in opposite direction thereto.

11. In a display device, as per claim 9, said screen being sharply inclined towards the light source in one direction, said images producing means being inclined in opposite direction thereto, and consisting of co-operative opaque, light-passing as well as colored instrumentalities.

OTTO SCHLETT.
